UNITED STATES PATENT OFFICE.

GOTTFRIED FISLER, OF CLEVELAND, OHIO.

ELECTRIC-CURRENT CORD HOLDER.

Application filed January 30, 1925. Serial No. 5,745.

The primary object of this invention is to provide means for supplying electric current to any of several forms of appliances, such means permitting movement of the appliance to different points while retaining the current conductor in a relatively taut position.

A further object is to provide a conductor carrier which is removably attachable to an electrical appliance or to a wall socket.

A still further object is to provide a conductor carrier attachable to an electric appliance, this carrier including a shell in which an arbor or reel is mounted, and a spring continually tending to entirely wind the conductor upon the arbor.

It is also an object to provide a novel form of mounting an arbor in a shell and a generally simplified construction such as will facilitate assembly and application of the device to use.

Other objects will be in part obvious and in part pointed out hereinafter.

In order that the invention and its mode of operation may be readily understood by those skilled in the art, I have in the accompanying illustrative drawings and detailed description based thereon pointed out the preferred embodiment of the same.

Figure 1 is a perspective view illustrating one application of my invention;

Figure 2 is a detail elevation of the cord and reel housing or casing;

Figure 3 is a detail view partly in section, one portion of the casing being removed;

Figure 4 is a cross sectional view taken substantially on the line 4-4 of Figure 3; and

Figure 5 is a sectional view in detail showing the structure and relation of one end portion of the arbor and its support.

In the accompanying drawings throughout which similar characters of reference designate like parts, this improved electric current cord holder is shown as comprising broadly a shell, which may be spherical or any other shape, attached removably to an electric iron and having one end of a current conductor secured to a rotatable arbor while its other end carries a plug removably arrangeable in any ordinary wall socket.

In constructing this device I form an open ring-like frame 6 which may be constructed from cast iron or the like material. This ring-like frame 6 is enlarged at four uniformly spaced points as is clear from Figures

2 and 3, one of the enlarged portions being attachable to a connector plug 8 by means of screw fasteners 9 or the like. This enlarged portion 7 is provided with a central opening 10 which communicates with relatively large openings 11 formed in the adjacent enlarged portions 12 through circumferential channels 13 as indicated in Figures 3 and 4. These channels serve to accommodate the short current conductors 14 which form a portion of an electric circuit between the plug 8 and a main conductor cord which will be hereinafter described.

A pair of bearing blocks 15 is secured to the inner face of the ring frame 6 by means of screw fasteners or the like 16, these blocks being so positioned as to close the aforementioned openings 11. Each of these bearing blocks is preferably constructed from bakelite and has a circular recess or cup 17 in its inner face for the reception of one of the ends 18 of an arbor 19. Sets of ball bearings 20 are arranged in these cups 17 whereby to rotatably support the arbor 19.

As a means for continually and uninterruptedly exerting a winding action on the arbor 19 to wind a conductor cord thereon I arrange adjacent the inner cupped faces of the bearing blocks 15, coil springs 21 of the clock spring type, one end of each spring being secured to a pin 22 rigidly fixed in an enlarged portion 23 of the ring frame 6. In order to prevent displacement of these springs I arrange upon the arbor 19, pairs of guard disks or plates 24 as shown in Figure 3. These disks, due to their relation to the springs, will positively hold them in their proper positions.

The main conductor cord 25 extends through an insulating sleeve 26 arranged in an opening formed in the enlarged portion 27, and has one end attached to a wall plug 28 while its other end is attached to a pair of spaced binding screws or the like 29 on the arbor. These screws are set into metal plugs 30, which serve as supports for the inner ends of longitudinal relatively fixed rods 31 whose other ends telescope into brush members 32 which normally move into contact with bolts or binding members 33 by means of coil expansion springs 34. This structure is quite clear in Figures 3 and 5 of the accompanying drawings. The current conducting cord 14 has its lower end fastened to the bolt or binding member 33.

A sheet metal casing is arranged over the

ring frame 6 and encloses all of the foregoing elements, with the exception of the screw plug 8, and is preferably made up of two semi-spherical members 36 whose edge portions fit one within the other and are so fastened by means of screw fasteners 35 as indicated in Figure 2 of the accompanying drawings. Each of these casing sections 36, has portions cut away to form recesses in 10 which the insulating sleeve and the base portion of the screw plug 8 will fit.

From the foregoing description it is obvious that an iron carrying an attachment of this character may be moved about upon 15 an ordinary ironing board without the usual inconvenience experienced due to the use of an unnecessarily long current conducting cord. With this device the cord is normally wound upon the arbor 19 in the casing and 20 due to the action of the coil springs 21 the portion of the cord outside of the casing will at all times remain relatively taut and consequently will not hinder manipulation of the iron or other appliance by a user. It 25 is quite obvious that this device is attachable to carpet sweepers and the like appliances, or may well be fixed directly in a wall outlet, in which event a lamp or the like could be attached to the outer end of the 30 current conductor 25.

Certain minor changes in the details of construction may be resorted to and such of these changes as may fall within the scope of the appended claim, I consider within the spirit of my invention. 35

I claim:—

A device of the character described comprising, a one-piece ring-like frame having the equi-spaced enlarged portions two of which are diametrically opposed and formed 40 with central openings, the third enlarged portion having an opening, a connector plug fixed to and extending outwardly from the third portion, said frame having a cord opening opposite the plug, and having external channels forming communication 45 between the first three openings, current conductors connected to the plug, and extending through said channels to the opposed central openings, bearing blocks arranged 50 over the inner ends of said central openings, a reel having electrical contact with said conductors and mounted in the blocks, a current conducting and extending through the cord opening and having electrical connection with the other conductors through 55 said reel, and a casing for said frame.

In testimony whereof, I affix my signature.

GOTTFRIED FISLER.
